UNITED STATES PATENT OFFICE

2,130,015

FEED MECHANISM FOR TABULATING MACHINES

Louis Jensen, Chicago, Ill., assignor to United Autographic Register Co., Chicago, Ill., a corporation of Illinois

Application February 13, 1936, Serial No. 63,779

4 Claims. (Cl. 197—133)

This invention relates to feed mechanism for a typewriting or tabulating machine, whereby continuous-form stationery strips may be fed around the rotatable platen roll without employing the usual presser mechanism provided in conjunction with the platen roll.

The primary object of the invention is to provide a simple feed mechanism which may be mounted on the platen carriage of the machine and be driven directly by the platen roll, advancing the stationery at the same peripheral speed as the platen.

Heretofore endless belts have been used to engage marginal perforations in the stationery strips and the belts have been looped directly around the platen. The objection to this arrangement is found in its lack of flexibility, that is, the stationery must be of a certain width and special perforations had to be provided in the stationery at the margins. The driving sprockets on the driving roll if not placed at the edges of the roll interfered with the typing face of the platen. In the present invention the register perforations usually provided in pairs near the center of the strip may be used. The endless belts being mounted remote from the platen do not interfere in any way with its usual operation. Preferably the mechanism is pivotally mounted on the carriage so that it may be tilted back to facilitate leading the stationery from the supply packet around the platen. The invention is illustrated in a preferred embodiment in the accompanying drawings, in which—

Fig. 1 is a broken front elevational view of a power driven platen roll provided with a mechanism embodying the invention; Fig. 2, a broken longitudinal sectional view taken as indicated at line 2—2 of Fig. 1, with dotted lines indicating the mechanism tilted back from its normal operative position; Fig. 3, a broken sectional view taken as indicated at line 3 of Fig. 1; Fig. 4, a broken transverse sectional view taken as indicated at line 4 of Fig. 3; Fig. 5, a broken elevational view showing a portion of the conveying belt and register pin mounting; Fig. 6, a sectional view of the same taken as indicated at line 6 of Fig. 5; Fig. 7, a broken longitudinal sectional view showing a modified form of conveyor belt, taken as indicated at line 7 of Fig. 8; Fig. 8, a broken transverse sectional view taken as indicated at line 8 of Fig. 7; and Fig. 9, a broken perspective view showing a portion of the modified endless belt.

In the preferred embodiment illustrated in Figs. 1-6, A designates a typewriting or tabulating

machine; B, an adjustable platen carriage provided with a rotatable platen roll B' which may be driven by suitable mechanism B²; C, a rearwardly extending main frame mounted on the carriage B; and D, an auxiliary frame which carries the feed mechanism.

The typewriting or tabulating machine A may be of any suitable construction and has type, not shown, adapted to strike continuous-form stationery 10 which is looped around the platen roll 10 B'. The platen carriage B is transversely adjustable on the machine A and provides journals for the rotatable platen B' which is driven by a motor and timing mechanism B² shown at the left of Fig. 1, through gears indicated generally at 11.

The rearwardly extending frame C is fixedly mounted on the carriage B by means of cap screws 12, and supports at its rear end a cross bar 13 on which is mounted a plate 14 which, as illustrated, may serve as a support for a zig-zag folded packet of stationery 15 from which the continuous-form strips 10 may be drawn. However, it may be preferred to place the packet in a container resting on the floor or a table in rear of the machine. The plate 14 then serves as a guide.

The auxiliary frame D comprises a pair of triangular brackets 16 which are pivotally supported on the cross bar 13 and support at their upper ends cross bars 17 and 18. A resilient presser member 19 is carried by bracket 19^a which is adjustably secured to the cross bar 18 by means by a thumb screw 19^b so that suitable pressure may be exerted downwardly against the plate 14 and insure proper withdrawal of the strips 10 thereover.

A plate-like member 20 is fixedly mounted on a housing 21 by means of spacing blocks 21^a and screws 21^b. The housing member has side walls 22, the lower ends of which are turned inwardly as indicated at 24 and are fixedly secured to the cross bars 17 and 18 by means of strap-like brackets 25 and screws 25^a. The member 20 is provided with longitudinal slots 26 through which register pins extend to engage perforations 10^a in the stationery. The upper end portion of the member 20 is curved upwardly as indicated at 27 to direct the stationery away from the pins at the top of the machine. In the side walls 22 are journaled a drive shaft 28 and an idler shaft 29 which are provided with sprocket wheels 30 around which may be looped the endless conveyor chains 31. As shown in Figs. 2 and 4 the idler shaft is provided at its ends with adjustable 55

heads 32 which may be moved in slots 33 to tension the endless chains.

As shown in Figs. 4, 5 and 6, register pins 34 are provided at regularly spaced intervals on the chains 31. The pins are formed by pressing a head 35 over upward extensions 36 provided on central links between the side links 37. The links 36 and 37 may be held together by ordinary pivot pins 38. Preferably the heads are provided with a base flange 39 which slides on the plate 20 and is adapted to move through openings 40 provided in the guide portions 27. The drive shaft 28, as shown in Fig. 1, extends laterally through a journal member 41 carried by the cross members 17 and 18. The end portion is provided with a spur gear 42 which in its normal operative position meshes with gear 43 provided on the platen carriage. The platen carriage B' is provided with a spur gear 44 which drives the gear member 43 by means of a train of idler gears 45 and 46. These gears cause the pins 34 to travel at the same speed as the face of the platen, B', as will be readily understood. One lateral edge portion of the plate-like member 20 has a hinge support 47 for a guide frame 48 having longitudinal bars 49 which are adapted to press the stationery strips 10 against the plate 20 and insure the register pins 34 coming into engagement with the register perforations.

In the modification illustrated in Figs. 7, 8 and 9, a lower drive shaft 50 is provided with pin wheels 52 having projections 52a adapted to engage perforations 54 provided in an endless metallic belt 55. An idler shaft 51 is provided with sheaves 53 for the belt. The belt may be formed of bronze tape or the like and is provided at regular intervals with outwardly extending pins 56 which are adapted to travel through slots 57 provided in a plate-like member 58. The member 58 is provided at its upper end with a guide portion 59 for directing the stationery from engagement with the pins. As best shown in Fig. 8 the plate-like member 58 is provided with cross members 60 which are bent downwardly as indicated at 61 to provide openings 62 through which the belts 55 may travel. The feed mechanism is provided with a guide device 63 similar to the one described above and the operation of the same.

To load either of the embodiments shown a latch member 64 is depressed and the auxiliary frame tilted back to the position indicated by the dotted lines in Fig. 2. This action will raise the presser member 19 and enable the operator to reach beneath the shaft 28 and direct a strip of stationery beneath guide member 65, on the platen carriage, and around the platen roll B'. The auxiliary frame may then be swung back into the position shown in Fig. 1 and the register perforations in the stationery brought into engagement with the first pair of register pins 34.

The register pins may then be advanced to tension the stationery through the power mechanism B' or by rotating a knob 66 provided at the end of the platen roll. The machine is then ready for use and the stationery will be advanced in timed relation to the movement of the platen.

The foregoing detailed description has been given for clearness of understanding only, and no unnecessary limitations should be understood therefrom, but the appended claims should be construed as broadly as permissible, in view of the prior art.

What I regard as new and desire to secure by Letters Patent, is:

1. In a duplicating machine, feed mechanism for advancing over impression receiving position stationery strips provided with register perforations, comprising: a frame having a plate-like surface mounted above and in rear of said impression receiving position, said surface being provided with longitudinally extending narrow slots; a drive shaft journalled in the lower end portion of said frame; an idler shaft journalled in the upper end portion of the frame; and a plurality of endless belts looped in driving connection around said shafts beneath the slots and provided with feed pins adapted to project through the slots into engagement with perforations in the stationery strips and slide on the plate-like surface.

2. A device as specified in claim 1, in which the upper ends of the slots are enlarged to permit the pins to pass through the plate-like surface and the upper end portion of said surface is bent upwardly and away from the belts so that the stationery will be automatically disengaged from the pins when reaching the upper ends of the frame.

3. A device as specified in claim 1, in which the frame is equipped at one lateral edge with a hinged guide member adapted to rest on stationery led over the plate-like surface of the frame and guide the stationery into engagement with the pins.

4. In a tabulating machine having a platen carriage equipped with a power driven platen roll, feed mechanism for stationery strips led around said platen, comprising: a frame mounted on the rear of said carriage and provided with a holder for a packet of zigzag folded stationery strips provided with register perforations; and an auxiliary frame mounted on the main frame and provided with a drive shaft geared to said platen, an idler shaft journalled in said auxiliary frame, endless belts, provided with pins, looped in driving relation around said shafts, said pins being adapted to engage perforations in stationery led from said packet around the platen, and a downwardly directed adjustable presser arm mounted on said auxiliary frame and adapted to bear against the stationery packet.

LOUIS JENSEN.
